ARMHOLE GARMENT AND METHOD
OF MAKING

William Nagel, Pelham, N. Y.

Application March 11, 1949, Serial No. 80,926

4 Claims. (Cl. 2—115)

1

This invention relates to garments made of woven textile material and provided with arm-holes so as to extend over and cover the front and back of the wearer. Such type of garments, which I term arm-hole garments, comprises men's women's and children's outer shirts and undershirts, blouses, jackets, vests, coats, smocks, pajamas and the like.

An important object of my invention is to provide an arm-hole garment capable of affording a trim and comfortable fit and which at the same time is adapted to yield in a crosswise direction between the shoulder blades to allow the wearer greater freedom of movement in bending over or in flexing the arms.

Another object of my invention is to provide an arm-hole garment of the above character in which the front and back portions of the garment are formed in one piece so as to avoid cross-seams in the vicinity of the shoulders where the garment is usually subjected to maximum stress.

Still another object of my invention is to provide an arm-hole garment of the above character in which the material comprising the back portion of the garment is cut on a bias to afford stretch between the shoulder blades.

Other objects and advantages will be apparent from the following detailed description of a preferred embodiment of the invention, reference being made to the annexed drawing in which:

Figure 1 is a front view of a men's outer shirt;
Figure 2 is a back view of the shirt;

Figure 3 is a layout of one of the two half-sections which are adapted to be stitched together to form the front and back portions of the shirt;

Figure 4 is a detailed cross-sectional view taken on the line 4—4 of Fig. 2 showing the manner in which the shirt sections are stitched together; and

Figure 5 illustrates the same garment construction embodied in the coat of a pair of men's pajamas.

In Figures 1 and 2 of the drawing are illustrated front and back views of a men's shirt made of woven cloth, the warp threads extending in the direction of the lines indicated in the drawing. The shirt is composed of two counterpart sections A and B, each section constituting a front portion 1 and a back portion 2 and the two sections being stitched together along a seam 3 extending vertically and medially along the back. Sleeves 4 and a collar 5 complete the shirt.

A layout of the shirt section A as cut from a

2

web of woven cloth is illustrated in Figure 3. The unitary front and back portions 1 and 2 are of approximately equal length, the side edges 6 and 7 of the front portion being disposed more or less parallel to the warp threads of the cloth and the corresponding side edges 6a and 7a of the back portion extending at an angle of approximately 45 degrees to the warp threads. A semi-circular-shaped cut-out 8 is provided adjacent the intersection of the side edges 6 and 6a, and a somewhat larger sized semicircular-shaped cut-out 9 is formed adjacent the intersection of the side edges 7 and 7a.

The shirt section B is of the same contour as the section A so that by reversing one of the sections and stitching together the juxtaposed corresponding inner side edges 6a of the two sections via the seam 3, the two cut-outs 8 co-operate to form the neck opening of the shirt.

The two outer side edges 7 and 7a of each of both sections are similarly stitched together closing the cut-outs 9 to form the arm-holes of the shirt. The inner side edges 6 of the two companion sections A and B overlap at the front of the shirt and are provided with button fastenings 11. The sleeves 4 are sewn onto the arm-holes and the collar 5 is secured to the neck opening in the usual manner. In order to strengthen the shirt at the seams the marginal edges of the material are double-folded and stitched down as indicated at 3a in Figure 4.

The coat C of a pair of men's pajamas shown in Figure 5 is illustrative of other arm-hole garments besides shirts to which the method of manufacture described above is applicable.

By reason of the construction just described, the front portion of the garment has its warp threads extending longitudinally and parallel to the center line of the garment in a conventional manner while in the back portion the threads are disposed on a bias relative to the center line thus allowing the material to stretch when the wearer bends over or flexes his arms. This construction not only adds to the comfort of the wearer but it obviates excessive strain upon the seams of the garment. Because the front and back portions of each of the companion sections A and B are made in one piece, the manufacture of the shirt is simplified while at the same time the usual shoulder seams in arm-hole garments is eliminated. Since such shoulder seams are especially subject to strain during the normal course of wear of a garment, an important cause of shirt damage is eliminated as a result of my garment construction. By the terms "center line" and "centrally"

as applied to the garment is meant a direction extending midwidth of the garment from its top (neck portion) to its bottom (tail portion). By the term "unitary" as used herein is meant in-one-piece-with, as distinguished from stitched or otherwise mechanically united.

Manifestly the arm-hole garment described above and the method of its manufacture are subject to modification by those skilled in the art without departing from the spirit of my invention as defined by the following claims.

I claim:

1. A method of making arm-hole garments which comprises severing two counterpart blanks of woven textile material, each blank constituting elongated, unitary and angularly related front and back portions of a garment with the warp extending substantially parallel to the length of the front portion and at an angle to the length of the back portion, forming cut-outs defining arm-hole and neck openings for the garment within opposite edges of each blank approximately mid-length thereof, assembling the blanks in side-by-side reversed relation and stitching together corresponding inner side edges of the back portions of the blanks to form a seam extending centrally down the back of the garment and also stitching together the outer side edges of each of the front and back portions of the blanks to close the arm-hole openings and form seams extending lengthwise along the sides of the garment.

2. A method of making arm-hole garments which comprises severing two counterpart blanks of woven textile material, each blank constituting elongated, unitary and angularly related front and back portions of a garment with the warp extending substantially parallel to the length of the front portion and at an angle to the length of the back portion, forming cut-outs defining arm-hole and neck openings for the garment within opposite edges of each blank approximately mid-length thereof, assembling the blanks in side-by-side reversed relation and stitching together corresponding inner side edges of the back portions of the blanks to form a seam extending centrally down the back of the garment, folding the assembled blanks upon a line extending crosswise between the arm-hole openings, stitching together the outer side edges of each of the front and back portions of the blanks to close the arm-hole openings and form seams extending lengthwise along the sides of the garment, and securing a collar to the margins of the neck opening.

3. An arm-hole garment of woven cloth comprising two sections of similar outline stitched together edge-to-edge along a seam extending lengthwise and centrally of the back of the garment and the two sections also being stitched together along seams extending lengthwise along the sides of the garment, each of said sections defining unitary, elongated front and back portions of the garment with the warp of the front portion extending substantially lengthwise thereof and the warp of the back portion extending at an angle to its length, and cut-outs in opposite longitudinal edges of said sections located approximately mid-length thereof, one cut-out of each section defining an arm hole and the other cut-out of the same section cooperating with a similar cut-out in the companion section to provide a neck opening in the garment.

4. A men's shirt made of woven cloth comprising two sections of similar outline stitched together edge-to-edge along a seam extending lengthwise and centrally of the shirt, each of said sections defining unitary front and back portions with the front portion extending parallel to the warp of the cloth and the back portion extending on a bias thereto, and the warp of the back portions of the two sections extending in reversed relation at approximately right angles to each other, semi-circular cut-outs in opposite longitudinal edges of each of said sections located approximately mid-length thereof, one cut-out of each section defining an arm hole and the other cut-out of the same section cooperating with a similar cut-out in the companion section to provide a neck opening in the garment, sleeves stitched to the edges of the arm-holes, a collar stitched to the edges of the neck opening and cooperating fastening means secured to the juxtaposed edges of the front portions of the two sections.

WILLIAM NAGEL.
